ROADWAY MARKER

Peter Hedgewick, Windsor, Ontario, Canada, assignor to
Reflex Corporation of Canada Limited, Amherstburg,
Ontario, Canada

Filed Jan. 12, 1970, Ser. No. 20,899

Term of patent 14 years

Int. Cl. D29—99

U.S. Cl. D72—1

FIG. 1

FIG. 2

FIG. 3

FIG. 4

FIG. 1 is a top plan view of the roadway marker embodying my new design;

FIG. 2 is a side view thereof on an enlarged scale taken on line 2—2 of FIG. 1, being partly in section;

FIG. 3 is an end elevational view thereof on an enlarged scale;

FIG. 4 is a perspective view thereof on a reduced scale.

The conventional prismatic surface pattern of the reflectors in each end of the roadway marker is indicated by cross-hatching in FIGS. 1, 3 and 4 for convenience of illustration, it being understood that the cross-hatching is continuous over the areas on which it appears.

I claim:

The ornamental design for a roadway marker, as shown and described.
